GAS MASK.

Application filed February 26, 1926, Serial No. 90,762, and in Germany March 30, 1925.

The invention is based upon the knowledge that poor or insufficient visibility through gas protective masks is a source of danger which cannot be too highly estimated, and which in certain circumstances increases to such an extent that the protective effect aimed at is entirely lost to the wearer of the mask. In gas protective masks used heretofore and made of pliable material having two circular eye-pieces or windows arranged either in the same plane or at an obtuse angle thus allowing perspective vision, there is the drawback that the field of view to the wearer is impaired in the downward direction, so that the wearer in order to look at his feet or on the ground must necessarily lower his head. The consequence is that the wearer in walking about is compelled to move his head continuously up and down. This has the effect of giving the wearer such a feeling of uneasiness and uncertainty, that, as experience proves, he is frequently induced to take the mask off prematurely and thus to divest himself of the contemplated protection.

According to the invention this drawback of inadequate visual power in gas protective masks is avoided by the fact that instead of circular eye-pieces made of glass, celluloid, cellulose or other suitable material use is made of eye-pieces of unequal breadth and length arranged in such manner that their longitudinal axes are in the direction of a line connecting the forehead and the chin. Therefore oval or elliptical eye-pieces are used, preferably such of which the outline corresponds to that of an egg, the broader part of the minor axis of the outline lying either below or above the eye. By providing eye-pieces of this shape the wearer without lowering or inclined the head and merely by correspondingly turning the eyes can look down to the ground whilst at the same

time the general front view is in no way obstructed.

In the accompanying drawing a constructional form of the invention is shown by way of example.

Fig. 1 is a front view of the mask as placed over the face of the wearer, and

Fig. 2 is a perspective sectional side view.

The mask *a* which is made of pliable material (leather, rubber or the like) is provided with eye-pieces *b* which are arranged either precisely or approximately in the same plane and allow a normal perspective field of vision. These eye-pieces are shaped similar to the outline of an egg, the longitudinal axis *c* being in the direction of a line connecting forehead and chin, the eyes of the wearer lying in the upper part of the eye-pieces. This egg-like or oval shape may be given preference when the eye-pieces are attached in the wall of the mask by binding, while a more lengthy shape is to be preferred when the eye-pieces are placed in metal mounts which are not connected in the wall of the mask by binding but by other means, for instance by pressing.

I claim:—

In a gas protective mask, the combination of a body of pliable material, and a pair of ovate eye pieces fixed in said body with the smaller ends pointing downwardly and extending downwards sufficiently far to permit a substantial increase of visual angle in a downward direction, the major axis of said eye pieces being substantially vertical, said eye pieces being located in said body to position the upper, larger end portions thereof in registry with the eyes of the wearer when the mask is worn.

In testimony whereof I have signed my name to this specification.

ALEXANDER BERNHARD DRÄGER.
